UNITED STATES PATENT OFFICE.

AUSTIN F. JACKSON, OF TAUNTON, MASSACHUSETTS, ASSIGNOR TO THE REED & BARTON CORPORATION, OF SAME PLACE.

DESIGN FOR A HANDLE FOR SPOONS, &c.

SPECIFICATION forming part of Design No. 22,065, dated December 20, 1892.

Application filed November 22, 1892. Serial No. 452,882. Term of patent 7 years.

To all whom it may concern:

Be it known that I, AUSTIN F. JACKSON, a citizen of the United States, residing at Taunton, in the county of Bristol and State of Massachusetts, have invented and produced a new and original Design for Handles of Spoons and other Similar Articles, of which the following is a specification, reference being had to the accompanying drawing, forming a part ⁵ thereof.

The figure is an upper or front face view of a spoon handle embodying my design.

The leading feature of my design is the special arrangement of the leaves, blossoms, and buds of the flower known as the "forget-me-not" applied to the handle as follows. The leaves, blossoms, and buds, are assembled into ¹⁵ a bunch which is tied by a ribbon with a bow-

knot *a* at the point where it joins the shank. From this point the leaves diverge upwardly ²⁰ and are surmounted by a cluster of blossoms *b*, and beyond this and forming the end of the handle is the flag or spray of undeveloped buds *c* slightly turned to one side. The outer edges of the leaves, blossoms, and buds ²⁵ impart their irregular outline to the margin of the handle.

What I claim is,

The design for the handle of spoons and other similar articles as herein shown and described. ³⁰

AUSTIN F. JACKSON.
